UNITED STATES PATENT OFFICE.

WILLIAM LOTTRIDGE, OF GRINNELL, IOWA, ASSIGNOR OF PART TO M. V. NICHOLS AND C. H. COTTER, BOTH OF OSAGE, IOWA.

REAPER MECHANISM.

SPECIFICATION forming part of Letters Patent No. 434,048, dated August 12, 1890.

Application filed February 15, 1889. Serial No. 300,074. (No model.)

To all whom it may concern:

Be it known that I, WILLIAM LOTTRIDGE, a citizen of the United States of America, and a resident of Grinnell, in the county of Poweshiek and State of Iowa, have invented an Improved Reaper Mechanism, of which the following is a specification.

My object is to narrow the machine when not in use without shifting a traction-wheel, 10 and to facilitate the movement of the cut grain from one endless carrier to another and at the same time straighten the straws, as required to produce a straight gavel and neat compact bound sheaf, and I accomplish the 15 results contemplated, as hereinafter set forth, pointed out in the claims, and illustrated in the accompanying drawings, in which—

Figure 1 is a top view of a reaper-frame to which my improved operative mechanism is 20 applied as required for practical use. Fig. 2 is a top view with one side removed, and Fig. 3 a transverse sectional view of a rotating fork of peculiar construction and specially adapted to be operated in combination with 25 endless carriers. Fig. 4 is a sectional view showing two rotating forks combined with two endless carriers that extend through different planes as required to advance cut grain from the sickle and elevate it to a binder. 30 Fig. 5 is a side view of the rotating forks combined with the platform-frame as required to advance grain from the end of the platform-carrier and to straighten the straws relative to each other.

35 A is the rear sill of the main carriage-frame, said frame being supported upon traction-wheels of uniform size and in parallel position at the opposite sides of the frame. Sill A is preferably made of channel-iron.

40 A² are the front and rear bars of the fixed section of the platform-frame, made of angle-iron and fixed to the irons A³, that extend from the main frame. A⁴ is a hinged section or extension of the platform-frame hinged to 45 the angle-iron bars or pieces A² in such a manner that it can be extended and supported in the same plane occupied by the fixed section or part of the platform, and also turned upward and inward, so that it will be 50 within the width of the main carriage-frame, as required to pass through gateways and to

facilitate the moving of the machine from one place to another.

To bring the sickle within the narrowed width of the machine I detach it from the 55 machine and place it on the narrowed platform.

Heretofore I have made a transformable reaper in which a traction-wheel was combined with an adjustable section of a platform in such a manner that the width of the machine could be narrowed; but I now hinge a section of the platform-frame to the machine so that it can be extended beyond the traction-wheel, as required for practical use, 60 and readily turned inward to overlap the fixed portion of the platform without changing the position of a traction-wheel or its supports.

B are drive-wheels on the axles of the traction-wheels.

B² is a driving-shaft in bearings fixed to the frame and connected with the drive-wheels B in such a manner that power will be transmitted and speed increased.

B³ is a rotating shaft in parallel position 75 with the shaft B² and connected therewith by means of sprocket wheels and chains, so that power will be transmitted thereto and speed increased.

c c are the mating parts of a grooved cam 80 or wheel detachably fixed to the shaft B³ in such a manner that they can be adjusted relative to each other, as required, to jointly engage the end of a lever to compensate for wear and to prevent undue friction. These 85 sections are cast in molds, and their faces, which are subject to wear, are preferably chilled and hardened.

c' is a lever pivoted to the frame and connected with the sickle in a common way at 90 one end and extended into the serpentine cam-groove produced by the mating parts c in such a manner that the rotary motion of the cam will impart a vibrating motion to the sickle, as required to cut grain, as the machine is advanced. Power is thus transmitted from the motion of the parallel traction-wheels to the sickle and the speed of the sickle increased. An anti-friction roller is placed on the end of the lever that extends 95 into the cam c c.

D are rotating rakes, that may vary in

length as desired, mounted in parallel position upon the platform and at right angles thereto, as required to engage and move and straighten cut grain advanced upon an end-
5 less carrier D². The upper rotating rake projects beyond the lower one and over the sickle, so that its tines will come in contact with straw that projects forward over the carrier and the sickle. These rakes are cylindrical
10 in form and constructed in such a manner that the tines will be thrust out to engage and move the grain and drawn in to prevent any straw from being carried around out of the line of advance in which the grain is to
15 be mowed.

f are the angular heads or ends of my rotating cylinder.

f' are integral circular flanges.

f'' are side pieces in the form of segments
20 fixed to the angular heads *f*, as required to produce a hollow cylinder.

g is a crank-shaft that extends through the axis of the heads *f*, its crank being eccentric thereto.

²⁵ 1 2 3 4 are tines bent around the crank of the shaft at their inner ends and put through perforations in the cylinder in such a manner that they will be carried around the shaft when the cylinder is rotated and the shaft is
30 stationary.

h is a gudgeon on the end of one of the heads *f*, that enters a bearing fixed to the frame in such a manner that it can be read-

ily connected with the driving mechanism by means of gearing, as shown in Figs. 1 and 5. 35 The shaft *g* extends into a bore in the axis of one of the heads *f* and through a bore in the axis of the other and into a fastening device *i*, that is fixed to the platform-frame in such a manner that the cylinder can be rotated 40 while the shaft remains stationary, as required to project the tines on one side of the cylinder only at each revolution, as shown in Figs. 2 and 3, and as required to take hold and let go of the cut grain that comes in contact therewith and is advanced thereby. 45

I claim as my invention—

1. In a grain-harvester having a fixed platform extending forward from the carriage-wheels, a platform-section hinged to the grain 50 end of said fixed platform so as to extend laterally and horizontally in front of the carriage-wheels and in the plane of the fixed platform, so that it can be readily turned upward and inward over the fixed section in front of 55 the carriage-wheels, for the purposes stated.

2. In a harvester, the combination, with the platform and carrier, of a rotating rake at the delivery end of the carrier, and a longer rotating rake above it extending forward over 60 the sickle, substantially as shown and described, for the purposes stated.

WILLIAM LOTTRIDGE.
